INDICATION APPARATUS

Earl M. Allen, Swissvale, Pa., assignor to The Union Switch & Signal Company, Swissvale, Pa., a corporation of Pennsylvania

Application October 9, 1942, Serial No. 461,379

6 Claims. (Cl. 246—122)

My invention relates to indication apparatus, and more particularly to indication apparatus for railway signal systems.

A railway signal system governing a track layout sometimes includes means for providing indications for the different signals, switches and track sections of the layout. These indications may be visual or audible, or both, and are usually given at the office in which there is located an operator who controls the switches and signals, line circuits being used to transmit the indications to the office. Such office may be, and frequently is, a relatively long distance from the location of the track layout, and it is in the interest of simplicity and economy if a plurality of different indications can be transmitted over a single line circuit.

Accordingly, a feature of my invention is the provision of novel and improved apparatus whereby a plurality of different indications are transmitted over a single line circuit consisting of two line wires, one wire of which may be a wire common to a plurality of circuits. Other features, objects and advantages of my invention will appear as the specification progresses.

I provide four different indications over a single line circuit by using four different forms of current. Steady or non-coded current of positive polarity provides a first indication, momentary current of positive polarity followed by coded current alternately positive and negative in polarity provides a second indication, steady or non-coded current of negative polarity provides a third indication, and momentary current of negative polarity followed by coded current alternately positive and negative in polarity provides a fourth indication. These four forms of current are supplied one at a time to a line circuit according to preselected conditions of the devices to be indicated, and the current is received at the receiving point or office by indication means characterized to respond differently to the polarity of the current and to the coded and non-coded conditions of the current. Such indication means is used to selectively control visual or audible indicators.

I shall describe one form of apparatus embodying my invention, and shall then point out the novel features thereof in claims.

The accompanying drawing is a diagrammatic view showing one form of apparatus embodying my invention when used to indicate the positions of the signals and the traffic conditions of a detector track circuit associated with a railway switch. It is to be understood, however, that my

invention is not limited to use with these particular devices, but this one application serves to illustrate the many places where apparatus embodying my invention is useful.

5 Referring to the drawing, the diagram at the upper right-hand portion of the drawing represents a stretch of railway track D—E which includes a track switch SW leading to a second track F. The track switch SW may be hand operated or power operated, or it may be a so-called "spring" switch. The track rails at this switch location are formed by the usual insulated rail joints with a detector track section 1T, and which section is provided with a track circuit including a track relay 1TR, the relationship of relay 1TR to the track circuit being indicated in the drawing by a dotted line 10. Track relay 1TR controls, in turn, a slow release repeater relay 1TP, this latter relay being energized by an obvious circuit including front contact 11 of track relay 1TR.

25 Three signals 2S, 4S and 6S are associated with the switch SW in the usual arrangement for governing traffic. Signal 2S governs traffic moving from right to left on track D—E, signal 4S governs traffic moving from track F to the track D—E, and signal 6S is provided with a top and a lower mechanism which govern traffic from left to right on track D—E and from track D—E 30 to track F, respectively. These signals may be of any standard form and are shown conventionally only. It is sufficient to point out that each of these signals is operable to display a stop indication and a proceed indication, each signal 35 being normally set to display its stop indication as illustrated in the drawing. The apparatus for controlling these signals is not shown, since such control apparatus forms no part of my invention and it would be of any standard arrangement.

40 It is contemplated, however, that the signals would be governed in part at least by an operator located at a remote office designated by the reference character OF, control being effected by the operator through the medium of a remote 45 control system, several of such systems being well-known to the art.

Each of these signals has associated therewith a signal repeater relay which is governed according to the aspect of the signal, and each 50 signal repeater relay is energized when and only when the associated signal displays its stop indication. These signal repeater relays are designated by the reference character GP, with a numeral prefix corresponding to the numeral of 55 the associated signal, and the relationship of

each such relay with the respective signal is indicated by a dotted line. Thus repeater relay 2GP is energized when and only when signal 2S displays its stop indication, relay 4GP is energized when and only when signal 4S displays its stop indication, and relay 6GP is energized when and only when both the top and lower mechanisms of signal 6S display a stop indication. Relay 4GP in turn governs a slow release repeater relay 4GPP, this latter relay being energized by an obvious circuit including front contact 12 of relay 4GP.

A source of direct current, such as battery FB is provided at the switch station. Battery FB is preferably of the so-called split battery type having a positive terminal B, a negative terminal N and a mid terminal C. The apparatus at the station also includes a coder CD which is shown as being of the relay type, the arrangement being such that a contact member 75 of the coder is operated to alternately engage contacts 75a and 75b as long as a winding 13 of the coder is supplied with current from a suitable source, such as battery FB. The rate at which contact member 75 is operated is preselected and may be, for example, 75 operations per minute.

A line circuit extends from the switch station to the office OF, this line circuit consisting of two line wires L1 and COM. The line wire COM may be a common wire used with other circuits and is connected to the mid terminal C of battery FB. The manner of supplying four different forms of current from battery FB to the line circuit according to the different positions of the signals and traffic conditions of section 1T will appear when the operation of the apparatus is described.

The office apparatus includes receiving means and a plurality of indicators, the receiving means being such as to distinguish between the polarity of the current supplied thereto and between coded and non-coded conditions of the current. This receiving means may take any one of several different forms, and as shown it comprises two indication relays 2GK and 6GK, a rectifying unit RC, a polar relay GKP and a slow acting relay GKPP. The indication relays 2GK and 6GK are neutral relays connected to the line circuit through the rectifier unit RC. One terminal of a winding of each of the relays 2GK and 6GK is connected to the common line wire COM by wire 14, the other terminal of the winding of relay 2GK is connected to line wire L1 through an asymmetric unit 15 of the unit RC, and the other terminal of the winding of relay 6GK is connected to the line wire L1 through an asymmetric unit 16 of unit RC. The asymmetric units 15 and 16 are disposed reverse to each other so that only current of one polarity is passed to relay 2GK and only current of the other polarity is passed to relay 6GK. I shall assume by way of illustration that relay 2GK is energized only by current of positive polarity and relay 6GK is energized only by current of negative polarity. Two asymmetric units 17 and 18 of the unit RC are preferably connected across the windings of relays 2GK and 6GK, respectively, to provide these relays with a slow to release characteristic. As will appear hereinafter, each relay 2GK and 6GK is provided with a slow release period slightly greater than the half code period of the coder CD at the station.

Relay GKP is a polar relay characterized by its armature 19 remaining in the position to which it was last moved when the relay is de-

energized. Relay GKP is controlled by the two indication relays, the arrangement being that when relay 2GK is picked up and relay 6GK is released, current flows from terminal B of an office battery OB through front contact 21 of relay 2GK, winding 20 of relay GKP and back contact 22 of relay 6GK to terminal N of battery OB, and relay GKP is then energized by current of normal polarity to operate its armature 19 to a normal or right-hand position to close normal polar contact 19-23; and when relay 6GK is picked up and relay 2GK is released current flows from battery terminal B through front contact 24 of relay 6GK, winding 20 of relay GKP and back contact 25 of relay 2GK to terminal N, and polar relay GKP is then energized by current of reverse polarity to operate its polar armature to a reverse or left-hand position to close reverse polar contact 19-26.

Relay GKPP is a neutral relay provided with preselected slow pick-up and slow release periods. This relay is also controlled by the two indication relays, current being supplied to relay GKPP from battery OB either by a circuit including front contact 27 of relay 2GK and back contact 28 of relay 6GK, or by a circuit including front contact 29 of relay 6GK and back contact 30 of relay 2GK. Thus relay GKPP is energized when either one of the two indication relays is picked up, and is deenergized when both indication relays are released and when both indication relays are picked up.

The office relays control visual indicators including four lamps 2L, 4L, 6L and 1TL for indicating signals 2S, 4S and 6S, and track section 1T, respectively. The manner of controlling these indicator lamps by the office relays will appear presently.

In describing the operation of the apparatus, I shall first assume that signal 2S is moved to its proceed position to permit a train to move from right to left on track D-E. Signal repeater relay 2GP is then deenergized and indication current of positive polarity flows from terminal B of battery FB through back contact 31 of relay 2GP, front contacts 32, 33 and 34 of relays 4GP, 6GP and 1TR, respectively, line wire L1, asymmetric unit 15 in its forward direction, winding of relay 2GK, wire 14 and common return wire to terminal C of battery FB. This indication current energizes relay 2GK and that relay is picked up closing front contacts 21 and 27. With front contact 21 closed, polar relay GKP is energized with current of normal polarity to close its normal polar contact 19-23, and with front contact 27 closed, relay GKPP is energized and picked up at the end of its slow pick-up period. A circuit for lamp 2L is now formed from terminal B of battery OB through front contact 35 of relay 2GK, back contact 36 of relay 6GK, lamp 2L, front contact 37 of relay GKPP, and normal polar contact 19-23 of relay GKP to terminal N of the battery, so that lamp 2L is illuminated to indicate the proceed indication position of signal 2S. Thus steady or non-coded indication current of positive polarity is applied to the line circuit to indicate the proceed indication of signal 2S.

When the train advances to the left and enters section 1T, the track relay 1TR is shunted to cause signal 2S to be returned to its stop indication in the usual well-known manner. This operation of signal 2S causes relay 2GP to be re-energized. The release of track relay 1TR to

open front contact 34 discontinues the supply of indication current of positive polarity, and indication relay 2GK at the office is deenergized and released at the end of its slow release period. When track relay 1TR is released, front contact 11 is opened and repeater relay 1TP is deenergized and releases at the end of its predetermined slow release period. During the slow release period of relay 1TP, current of negative polarity flows from terminal C of battery FB through line wire COM, wire 14, winding of indication relay 6GK, asymmetric unit 16 in its forward direction, line wire L1, back contact 38 of relay 1TR, and front contact 39 of relay 1TP to terminal N of battery FB, and indication relay 6GK is energized. The picking up of relay 6GK to open back contact 36 causes lamp 2L to be extinguished. The opening of back contact 28 of relay 6GK causes relay GKPP to be deenergized but relay GKPP remains picked up due to its slow release characteristic. The slow release period of relay 2GK is short as compared to the slow release period of relay 1TP and consequently relay 2GK releases while relay 6GK is energized by current of negative polarity. With relay 2GK released and relay 6GK picked up, polar relay GKP is energized at reverse polarity to close reverse polar contact 19-26, and the energization of relay GKPP is reversed causing relay GKPP to release at once. It is to be observed that no false illumination of indicator lamp 4L results during the slow release period of relay 2GK because relay GKPP is held picked up due to its slow release characteristic. The slow release period of repeater relay 1TP is long enough to assure release of relay 2GK and operation of polar relay GKP but is less than the pick-up period of relay GKPP, and hence before relay GKPP is picked up due to this reverse energization, the relay 1TP releases to open front contact 39 and discontinue the supply of indication current of negative polarity. With both track relay 1TR and its repeater relay 1TP released, the indication current is coded to be alternately positive and negative in polarity by action of the coder CD, the positive terminal B of battery FB being connected to line wire L1 through coder contact 75-75a and back contacts 40 and 38 of relays 1TP and 1TR, respectively, and the negative terminal N of the battery being connected to the line wire L1 through coder contact 75-75b and back contacts 40 and 38. With the indication current thus coded to be alternately positive and negative in polarity, the two indication relays 2GK and 6GK are alternately energized and both are held picked up because the slow release period of each relay 2GK and 6GK is slightly greater than the half code period of coder CD. With both indication relays 2GK and 6GK picked up, relays GKP and GKPP are both deenergized. A circuit is now formed from terminal B of battery OB through front contact 35 of relay 2GK, front contact 41 of relay 6GK, lamp 1TL, back contact 42 of relay GKPP and reverse polar contact 19-26 of relay GKP to terminal N, and the lamp 1L is illuminated to indicate the occupancy of section 1T. Thus occupancy of section 1T is indicated by an indication current that is of negative polarity for a predetermined interval and then coded to be alternately positive and negative in polarity.

When this train vacates section 1T, the track relay 1TR is picked up to discontinue the supply of indication current, with the result that the in-

dication lamp 1TL becomes dark, and the apparatus is restored to its normal condition.

Assuming signal 6S is operated to its proceed indication position to permit a train to move from the left to the right on track D-E, the relay 6GP is deenergized and indication current flows from terminal C over the common line wire COM, wire 14, winding of relay 6GK, asymmetric unit 16 in its forward direction, line wire L1, front contact 34 of relay 1TR, and back contact 43 of relay 6GP to terminal N of battery FB, and indication relay 6GK is energized. With relay 6GK picked up to close front contacts 24 and 29, polar relay GKP is energized with current of reverse polarity to close its reverse polar contact 19-26 if that contact is not already closed, and relay GKPP is energized and picked up at the end of its slow pick-up period. A circuit is now formed from terminal B of battery OB through back contact 44 of relay 2GK, front contact 45 of relay 6GK, lamp 6L, front contact 46 of relay GKPP, and reverse polar contact 19-26 of relay GKP to terminal N, and lamp 6L is illuminated to indicate the proceed indication of signal 6S. Thus signal 6S is indicated by steady or non-coded indication current of negative polarity.

When the train enters section 1T and shunts track relay 1TR, the signal 6S is restored to its stop indication and relay 6GP is energized. When the track relay 1TR is deenergized, the repeater relay 1TP is also deenergized and releases at the end of its slow release period. During the slow release period of repeater relay 1TP, indication current of negative polarity is still supplied to the line circuit through front contact 39 of relay 1TP and back contact 38 of relay 1TR and then upon the release of repeater relay 1TP to close back contact 40 the circuit is completed through the coder contacts and the indication current is coded to be alternately positive and negative in polarity. When the current is thus coded both relays 2GK and 6GK are energized and relays GKP and GKPP are deenergized with the result that the indication lamp 6L is extinguished and lamp 1TL is illuminated to indicate occupancy of section 1T. Furthermore, when this train moving to the right vacates section 1T, the apparatus is restored to its normal position in the manner already explained.

Assuming next that the signal 4S is operated to its proceed indication for a traffic movement from track F, the repeater relay 4GP is deenergized and released when the signal 4S is set at its proceed indication, and repeater relay 4GPP is in turn deenergized and released at the end of its slow release period. During the interval relay 4GP is released and relay 4GPP is picked up, indication current of positive polarity flows from terminal B of battery FB through front contact 47 of relay 4GPP, back contact 48 of relay 4GP, front contacts 33 and 34 of relays 6GP and 1TR, respectively, line wire L1, asymmetric unit 15, winding of relay 2GK, wire 14 and common return wire to terminal C of battery FB and the indication relay 2GK is energized. With relay 2GK picked up, polar relay GKP is operated to close its normal polar contact and the slow acting relay GKPP is energized but is not at once picked up due to its slow pick-up period. The slow release period of relay 4GPP is less than the slow pick-up period of relay GKPP, and hence relay 4GPP is released to open front contact 47 and discontinue the supply of indication current of positive polarity prior to the picking up of relay GKPP. With both relays 4GP and 4GPP released, the

indication current is coded to be alternately positive and negative in polarity due to the action of coder CD, terminal B of battery FB being connected to line wire L1 through coder contact 75-75a, back contacts 49 and 48 of relays 4GPP and 4GP, and front contacts 33 and 34 of relays 6GP and 1TR; and terminal N of battery FB being connected to line wire L1 through coder contact 75-75b and the previously traced circuit connection. Both indication relays 2GK and 6GK are now energized and picked up and a circuit is formed from terminal B of battery OB through front contacts 35 and 41 of relays 2GK and 6GK, respectively, lamp 4L, back contact 50 of relay GKPP, normal polar contact 19-23 of relay GKP and terminal N of battery OB, and lamp 4L is illuminated to indicate the proceed indication of signal 4S. Hence signal 4S is indicated by an indication current that is momentarily of positive polarity and then coded to be alternately positive and negative in polarity.

When the train on track F advances past signal 4S and enters section 1T to shunt track relay 1TR, the signal 4S is restored to its stop indication and relay 4GP is reenergized, and the supply of coded indication current is discontinued. However, indication current of negative polarity is supplied to the circuit during the slow release period of the track repeater relay 1TP in the manner previously explained, with the result that indication relay 6GK is retained energized and relay 2GK is deenergized and released causing polar relay GKP to be operated to its reverse position. Slow acting relay GKPP is also energized but before the end of its slow pick-up period the track repeater relay 1TP is released causing coded indication current to be supplied to the circuit so that both indication relays 2GK and 6GK are again energized and picked up, and the relay GKPP is no longer energized. With both relay 2GK and 6GK picked up, polar relay GKP operated to its reverse position and relay GKPP released, the indication lamp 1TL is illuminated to indicate occupancy of the track section 1T in the manner explained hereinbefore.

It is to be seen, therefore, that any one of these four forms of indication current can be supplied to the circuit to control a corresponding indicator at the office, and that the form of indication current can be changed from any one form to any one of the other forms and a corresponding change of indicators will be accomplished. Indication apparatus of the arrangement here disclosed has the advantage that four different indications can be transmitted over a single two-wire line circuit with standard types of relays.

Although I have herein shown and described but one form of indication apparatus embodying my invention, it is understood that various changes and modifications may be made therein within the scope of the appended claims without departing from the spirit and scope of my invention.

Having thus described my invention, what I claim is:

1. In combination with an office and a station connected by a line circuit, a source of direct current at said station, a first and a second device at said station and each operable to a first and a second condition and each device governing a slow acting relay according to its condition; a coder at said station, circuit means including contacts of said coder and contacts governed by said devices and said slow acting relays to supply

from said source to said line circuit non-coded current of positive polarity for a predetermined interval followed by coded current alternately positive and negative in polarity and non-coded current of negative polarity for a predetermined interval followed by coded current alternately positive and negative in polarity in response to the second condition of the first and second devices respectively, office indication means including a polar relay and a code responsive means to receive current from said line circuit and differently responsive to said two forms of current thus supplied to the line circuit at said station.

2. In combination with an office and a station connected by a line circuit, a source of direct current at said station, a first and a second device at said station each operable to a first and a second condition, a slow acting relay governed by said second device, circuit means controlled by said first device to connect said source to said circuit to supply non-coded current of a pre-selected polarity in response to the second condition of the first device, a coder at said station, other circuit means including contacts of said coder and contacts controlled by said second device and by said slow acting relay to connect said source to said circuit to supply non-coded current of a pre-selected polarity for a predetermined interval followed by coded current alternately positive and negative in polarity in response to the second condition of the second device, office relay means connected to said circuit and differently responsive to the polarity of the current received and to non-coded and coded current, and office indication means governed by said office relay means to display one indication in response to the second condition of said first device and to display a second indication in response to the second condition of the second device because of said different forms of current supplied to the line circuit.

3. In combination with an office and a station connected by a line circuit, a source of direct current at said station, a first and a second device at said station each operable to a first and a second condition, a slow acting relay governed by said second device, circuit means controlled by said first device to connect said source to said circuit to supply non-coded current of a pre-selected polarity in response to the second condition of the first device, other circuit means including a coder controlled by said second device and by said slow acting relay to connect said source to said circuit to supply non-coded current of a pre-selected polarity for a predetermined interval followed by coded current alternately positive and negative in polarity in response to the second condition of the second device, a pair of office indication relays a first one being connected to said line circuit through a first asymmetric unit and the second one being connected to the line circuit through a second asymmetric unit, said asymmetric units disposed reverse to each other to energize said first relay in response to current of said pre-selected polarity and to energize both relays in response to said coded current, a slow pick-up relay controlled by the indication relays to be energized when said first indication relay is energized but not when both indication relays are energized, a first indicator supplied with current through a front contact of said slow pick-up relay, and a second indicator supplied with current through front contacts in series of said indication relays.

4. In combination with a railway track switch having three signals and a track section associated therewith, a repeater relay for each of said signals energized when and only when the respective signal indicates stop, a track circuit including a track relay for said section, two slow release repeater relays one governed by said track relay and one governed by a selected one of said signal repeater relays, a source of direct current and a coder at said switch, a remote office, a two-wire line circuit extending from the switch to said office, a first circuit means including a back contact of a first one of said signal repeater relays to connect said source to said circuit to supply current of positive polarity, a second circuit means including a back contact of a second one of said signal repeater relays to connect said source to said circuit to supply current of negative polarity, a third circuit means including contacts of said track relay and of its repeater relay and of said coder to connect said source to said circuit to supply current of positive polarity during the slow release period of the track repeater relay and then coded current alternately positive and negative in polarity, a fourth circuit means including contacts of said one signal repeater relay and its repeater relay and of said coder to connect the current source to said circuit to supply current of negative polarity during the slow release period of the last mentioned repeater relay and then coded current alternately positive and negative in polarity, and office indication means receiving current from said circuit and characterized to respond differently for each of said different forms of current thus supplied to said line circuit at said switch.

5. In combination, a first and a second indication relay each connected to a line circuit through an asymmetric unit, the two asymmetric units being disposed reverse to each other, a polar relay reversibly energized by alternative circuits one including in series a front contact of said first relay and a back contact of said second relay and the other circuit including in series a front contact of said second relay and a back contact of said first relay, a slow pick-up relay energized by alternative circuits one including in series a front contact of said first relay and a back contact of said second relay and the other circuit including in series a front contact of said second relay and a back contact of said first relay; a first indicator controlled through a front contact of said first relay, a front contact of said slow pick-up relay and a normal polar contact of said polar relay; a second indicator controlled through

a front contact of said second relay, a front contact of said slow pick-up relay, and a reverse polar contact of said polar relay; a third indicator controlled through a front contact of each of said first and second relays and a normal polar contact of said polar relay; a fourth indicator controlled through a front contact of each of said first and second relays and a reverse polar contact of said polar relay; and supply means to supply to said line circuit steady current of positive polarity, or steady current of negative polarity, or momentary current of positive polarity followed by current alternately positive and negative in polarity or momentary current of negative polarity followed by current alternately positive and negative in polarity.

6. In combination, an office and a station connected by a two-wire line circuit, a source of direct current and a coder at said station, four devices at said station, four repeater relays one controlled by each of said devices, two slow release relays one controlled by each of two pre-selected ones of said repeater relays, a first circuit means including contacts of one of the two preselected relays and its slow release relay and contacts of said coder to connect said source to said line circuit to supply current of positive polarity during the slow release period of that slow release relay and then coded current alternately positive and negative in polarity, a second circuit means including contacts of the other one of said preselected relays and its slow release relay and contacts of said coder to connect said source to said line circuit to supply current of negative polarity during the slow release period of that slow release relay and then coded current alternately positive and negative in polarity, a third circuit means including a contact of a third one of the repeater relays to connect said source to said line circuit to supply steady current of positive polarity, a fourth circuit means including a contact of the fourth one of said repeater relays to connect said source to said line circuit to supply steady current of negative polarity, two office relays connected across the line circuit through asymmetric units with said units disposed reverse to each other, a polar relay and a slow pick-up relay each controlled by said office relays, four office indicators one for each of said devices; and office circuit means including contacts of said office relays, said polar relay and said slow pick-up relay to selectively control said indicators in response to the currents supplied by said four circuit means.

EARL M. ALLEN.
